(57) CLAIM

The ornamental design for a pump with housing, as shown and described.

DESCRIPTION

FIG. 1 is a front elevational view of a pump with housing showing my new design;

FIG. 2 is a rear elevational view thereof;

FIG. 3 is a top plan side view thereof;

FIG. 4 is a view taken from the left side thereof;

FIG. 5 is a bottom plan view thereof;

FIG. 6 is a view taken from the right side thereof;

FIG. 7 is a front elevational view thereof with the front of the housing removed showing the pump and rear of the housing in front elevational view;

FIG. 8 is a view of the pump with the front of the housing removed of FIG. 7 shown in front perspective view; and,

FIG. 9 is a front perspective view of the rear of the pump housing with the front of the housing and pump removed.
